COMBINED SIGNAL AND TURN INDICATOR FOR MOTOR VEHICLES

George Lyle Dennis, Didsbury, Manchester, England, as-
signor to G. L. Dennis Limited, a company of Great
Britain and Northern Ireland

Filed May 23, 1962, Ser. No. 70,253

Term of patent 7 years

Claims priority, application Great Britain Dec. 22, 1961

(Cl. D48—32)

Fig.1.

Fig.2.

Fig.3.

Fig.4.

FIG. 1 is a perspective view of a combined signal and turn indicator for motor vehicles showing my new design;
FIG. 2 is a front elevational view thereof;
FIG. 3 is a rear elevational view thereof; and
FIG. 4 is a side elevational view thereof.

I claim:

The ornamental design for a combined signal and turn indicator for motor vehicles, as shown.
